UNITED STATES PATENT OFFICE

FABIUS M. BUTLER, OF SEATTLE, WASHINGTON

ACCELERATOR ATTACHMENT

Application filed August 15, 1927. Serial No. 212,945.

This invention relates to accelerators as used in connection with engines of automobiles or similar motor vehicles. More particularly, the invention relates to an accelerator attachment that is adapted to be actuated by the knee or leg of the vehicle driver as distinguished from accelerator of the foot or hand operated types.

The principal object of the present invention is to provide an accelerator of the above stated character that may be installed without requiring the removal of or any alteration in the parts with which it is associated, and which does not interfere with independent use of the accelerator mechanisms, or devices, with which a vehicle may already be equipped.

More specifically stated, it is the object of this invention to provide an accelerator attachment comprising a control lever adapted to be operatively supported from the instrument board, or any other conveniently located, fixed part of the vehicle, and which extends to a position at which it may be moved laterally by the knee or leg of the vehicle driver, and when so moved, will actuate certain devices connected with and controlling the action of the throttle valve of the vehicle carburetor.

It is also an object of the invention to provide a device of the above type having certain features of adjustment that makes it adaptable for use by different drivers as well as in various positions and on cars of various types.

A still further object is to so construct the device that it is most suitable for use on Ford automobiles, although not confined in its use to this particular make of vehicle.

Other objects of the invention reside in the various details of construction and in the combination of parts as is hereinafter described.

In accomplishing these objects, I have provided the improved details of construction, the preferred forms of which are illustrated in the accompanying drawings, wherein—

Figure 1 is a perspective view, illustrating an accelerator attachment embodied by the

present invention and one method of mounting it.

Figure 2 is a perspective view of the accelerator attachment and certain parts of the vehicle with which it is associated.

Figure 3 is a cross sectional view of the instrument board, showing the attachment thereto of a supporting bracket whereby the control lever of the accelerator is operatively supported.

Figure 4 is a detail section of the ball and socket connection between the inner end of the accelerator lever and a connecting rod.

Figure 5 is a plan view of the mechanism as installed.

Figure 6 is a perspective view, showing the method of and means for attaching the device to a steering column.

Figure 7 is a perspective view illustrating the use of the present device in connection with a foot throttle device.

Referring more in detail to the drawings—

1 designates what may be the instrument board of an automobile of a type with which the present device is particularly adapted for use, 2 the steering column which extends in a downwardly inclined position through the instrument board, and 3 the steering shaft which is equipped at its upper end with a steering wheel 4. Contained within the steering column, alongside of the steering shaft, is a rod 5 which, at its upper end, is provided with a laterally extending, actuating lever 6 and, near its lower end, has a short, downwardly extended lever 7 fixed thereto. This lever 7 is connected, as will presently be described, with the throttle valve actuating lever 8 of the carburetor 9 so that, by adjustment of the lever 6, the said valve will be adjusted accordingly for the admitting of more or less fuel to the engine.

As was previously stated, it is one of the objects of this invention to provide an accelerator attachment that may be installed for use independently of the accelerator mechanism already applied to the car but which, at the same time, will not prevent independent use of the latter. The device which I have provided, in its preferred form, consists of a control lever formed with leg portions 11 and 12

12 at right angles to each other, with the portion 11 slidably and rotatably fitted within an opening 13 that is bored through a bearing and supporting block 14, which, in turn, is supported pivotally from the instrument board by means of a bracket 15; the bracket having a vertically directed portion secured to the board by means of one or more bolts, or rivets, 16 and a laterally turned foot 15' provided with an aperture 17 within which a shank 14' extending from the block 14 is pivotally secured. The portion 12 of the control lever, which extends when in use to a position overlying the forward edge of the vehicle seat, is telescopically fitted within a co-extensive tubular member 18 which is equipped at its rearward end with a pad 19 against which the vehicle operator may press the leg or knee to swing the lever laterally.

20 Connected to the end of the leg portion 11, preferably by means of a ball and socket connection as designated at 20 in Figure 4, is a connecting rod 21 which extends downwardly and forwardly through an opening 22 provided in the dash board 23, and, at its lower end, is connected through the intermediacy of a short chain 24, provided for the purpose of easy adjustment, with a leg 25 of a pivotally mounted bell crank 26 having its other leg 27 connected by means of a rod 28 with the throttle valve actuating lever 8 of the carburetor. The bell crank 26 is mounted pivotally by means of a bracket member 29 which is fastened by a bolt 30 to the side of the vehicle engine designated at 31 in Figure 5.

40 In order that the throttle will be closed when not held open, I have attached a small coiled spring 32 to the bell crank leg 27 and to a fixed part of the steering gear, as shown in Figure 5.

45 With the parts of the device so constructed, arranged and connected together in the manner described, it is readily apparent that lateral swinging movement of the control lever incident to the application of pressure against the pad 19 will cause the throttle valve of the carburetor to be actuated through the various connections provided to admit more or less fuel to the vehicle engine and, when the pressure is removed, the spring 32 brings the parts back to closed position.

50 To provide for actuation of the device by the regular throttle equipment, I apply a slip sleeve 35 about the rod and connect this by a link 36 with the lever 7 or the throttle rod and fix a collar 37 on the rod 28 against which the end of the sleeve may abut. This provides that, when the throttle lever is adjusted to open the throttle, the sleeve will engage the stop and through it actuate the rod 28 to open the throttle. Also, this provides a slip connection that permits use of the present equipment without interference 65 by the regular equipment.

In Figure 6 I have illustrated the manner of supporting the mechanism from the steering column. For this purpose, I provide a bracket 40 that is fixed rigidly to the column by a clamping plate 41 and bolts 42. The bracket extends laterally to a proper position and there is provided with an opening for pivotally receiving the mounting shank of the block 14. The bracket 40 may be adjusted along the column to a desired position and may, if desired, be provided with a series of apertures 43 for receiving the mounting shank of the block 14 so as to provide for a proper, or desirable, positioning of the control lever.

80 In Figure 7 is illustrated the application of the mechanism for use in connection with a foot throttle device. In this view, 50 designates what may be a foot pedal of any suitable character having operative connection with the throttle valve of the carburetor whereby downward pressure in the pedal causes the throttle to open. Fixed to floor, or dash board, is a bracket 51 to which a bell crank 52 is attached by a pivot bolt 53. One arm of the crank overlies and bears against the pedal 50 and the other is connected by a link 54 to the lever arm 11. With this arrangement, movement of the control lever actuates the throttle pedal 50 to produce the same results as is provided by the construction and connections previously described.

85 A feature of the present construction resides in its adaptability to various persons and various cars. It will be noted that the effective length of the control lever may be varied as is required to suit different persons through the telescopic connections of the parts 12 and 18 and that, by slidably adjusting the lever portion 11 through the block 14, the pad may be brought into proper relation to the knee. When the device is not in use, the control lever may be swung upwardly and out of the way as indicated in dotted lines in Figure 1, to permit ready passage of the driver from or to the seat.

90 What I claim is:

1. In a vehicle of the character described in combination with the throttle member, an accelerator means comprising a pivoted support, a control lever slidable therein and operatively connected with the throttle member and extended to a position suitable for actuation by lateral movement of the knee or leg of a person in the driver's seat.
2. In a vehicle of the character described in combination with the fuel throttle mechanism, an accelerator attachment comprising a pivoted support, a control lever slidable therein and having operative connection at one end with the throttle mechanism and having an extension member at its other end adapted to be adjusted for use to a substantially horizontal position adjacent the knee or

- leg of the person in the driver's seat, and when not in use, to be adjusted forwardly to a position spaced substantially from the driver's seat.
5. In a vehicle of the character described having an instrument board and a fuel throttle mechanism, an accelerator attachment comprising a bearing member pivotally supported from the instrument board, a control lever swingingly supported by the bearing and extended to a position suitable for actuation by the knee or leg of a person in the driver's position and means connecting the lever and throttle mechanism whereby the latter will be actuated in accordance with swinging movement of the lever.
4. In a vehicle of the character described having an instrument board and a fuel throttle mechanism, an accelerator attachment comprising a bearing block pivotally supported from the instrument board, a control lever extended through the block and swingingly supported thereby with its rearward end adapted for adjustment to a position suitable for actuation by the knee or leg of a person in the driver's seat, and mechanism operatively connecting the forward end of the lever with the throttle mechanism.
5. In a vehicle of the character described having an instrument board and a fuel throttle mechanism, an accelerator attachment comprising a bearing pivotally supported from the instrument board, a control lever comprising forward and rearward portions formed substantially at right angles to each other with the forward portion slidably adjustable within the bearing and the rearward portion extended to a position suitable for lateral actuation by the knee or leg of a person in the driver's seat, and mechanism connecting the end of the forward portion with the throttle mechanism whereby the latter will be actuated in accordance with movement of the control lever.
6. In a vehicle of the character described having an instrument board and a fuel throttle mechanism, an accelerator attachment comprising a bracket fixed to the instrument board, a bearing block pivotally supported by the bracket having an opening therethrough, a control lever comprising forward and rearward portions formed substantially at a right angle to each other; said forward portion being slidably adjustable and rotatably contained in the block opening, and said rearward portion being adapted for adjustment to a position suitable for actuation by lateral movement of the knee or leg of a person in the driver's seat and mechanism connecting the end of the forward portion of the lever with the throttle mechanism whereby the latter will be actuated in accordance with movement of the control lever.
7. In a vehicle of the character described having an instrument board and a fuel throt-
- tle mechanism, an accelerator attachment comprising a bracket fixed to the instrument board, a bearing block pivotally supported by the bracket having an opening therethrough, a control lever having a laterally turned, forward end portion slidably and rotatably contained in the block opening and operatively connected with the throttle mechanism and having a rearwardly extending portion provided with an extension member that is adjustable to a position suitable for laterally actuation by the knee or leg of a person in the driver's seat. 70
8. In a vehicle of the character described having an instrument board and a fuel throttle mechanism, an accelerator attachment comprising a bracket fixed to the instrument board, a bearing block pivotally supported by the bracket having an opening therethrough, a control lever having a laterally turned forward end portion slidably and rotatably contained in the block opening and operatively connected with the throttle mechanism and having a rearwardly extended portion that is adjustable to different positions transversely of the vehicle by shifting of the forward portion in said block, an extension sleeve adjustably fitted on the rearward end of the lever and a knee pad in said sleeve; said lever mechanism being adapted to be positioned by adjustment of the parts for actuation by lateral movement of the knee or leg of a person in the driver's seat. 80
9. In a vehicle of the character described having an instrument board, a carburetor having a throttle control lever, an accelerator attachment comprising a bracket that is fixed to the instrument board, a bearing block pivotally supported by the bracket and having an opening therethrough, a control lever comprising forward and rearward portions formed substantially at right angles to each other; said forward portion being slidably adjustable and rotatably contained in the block opening and said rearward portion being adapted for adjustment to a position suitable for actuation by lateral movement of the knee or leg of a person in the driver's seat, a bell crank lever pivotally mounted on a fixed part of the vehicle, a link connecting one leg of the bell crank with the throttle lever and a link operatively connecting the other leg of the bell crank with the end of the forward portion of the control lever. 100
